UNITED STATES PATENT OFFICE.

FREDERICK C. HOFFMAN, OF THOMASTON, CONNECTICUT, ASSIGNEE TO SETH THOMAS CLOCK CO., OF THOMASTON, CONNECTICUT, A CORPORATION.

CASE-BACK FOR NICKEL ALARM-CLOCKS.

1,120,651.

Specification of Letters Patent.

Patented Dec. 8, 1914.

Application filed March 21, 1914. Serial No. 826,412.

To all whom it may concern:

Be it known that I, FREDERICK C. HOFFMAN, a citizen of the United States, residing at Thomaston, in the county of Litchfield 5 and State of Connecticut, have invented a new and useful Improvement in Case-Backs for Nickel Alarm-Clocks; and I do hereby declare the following, when taken in connection with the accompanying drawings and 10 the characters of reference marked thereon, to be a full, clear, and exact description of the same, and which said drawings constitute part of this application, and represent, in—

15 Figure 1 a view in rear elevation of a nickel clock case-back constructed in accordance with my invention. Fig. 2 and edge view thereof. Fig. 3 a view in horizontal section on the line *a—b* of Fig. 1 of a clock-case provided with my improved case-back.

20 My invention relates to an improved back for the cases of that class of small cylindrical sheet-metal clocks in which a relatively large bell is located at the back of the 25 case and concentric therewith, the object being to provide a simple, cheap, convenient and substantial case-back for carrying the bell.

With these ends in view, my invention 30 consists in a case-back for sheet-metal clock-cases, the said case-back having certain details of construction and combinations of parts as will be hereinafter described and pointed out in the claim.

35 In carrying out my invention as herein shown, I employ a struck up sheet-metal case-back 2 formed upon its outer edge with an annular flange 3 adapted in diameter to fit snugly within the rear edge of a cylindrical sheet-metal case-band 4 forming the 40 case proper. The center of the case-back 2 is formed with a concentric rearwardly projecting bell-standard 5 truncated in shape and having a flat outer bearing-face 6 for 45 the concentrically arranged bell 7 the forward edge of which extends into a deep, wide, annular channel or concentric recess 8 encircling the standard 5. The retaining-flange 3 is stopped from being inserted too 50 far forward into the case-band 4 by means

of an over-hanging bead 9. The bell 7 is secured in place by means of two screws 10, 10, passing through holes in the bearing-face 6 of the standard 5 into a heavy sheet-metal washer-like reinforce 11 placed 55 against the inner wall of the said bearing-face 6 and secured in place by having its inner edge 12 set inward and folded outward and over the inwardly set edge 13 of a large opening formed in the center of the 60 said face 6 the said edges 12 and 13 being sufficiently set inward so as not to project beyond the plane of the bearing-face 6. The reinforce 11, it will be observed, corresponds in diameter to the diameter of the extreme 65 outer end of the bell-standard 5 which it reinforces. By use of this reinforce, the case-back 2 though made of very light sheet-metal, is reinforced so as to permit the bell 7 to be solidly attached to it by means of the 70 screws 10 which are threaded into the relatively thick metal of the gromet-like reinforce.

I claim:—

A combined case-back and bell-support 75 for clock cases, having a one-piece circular case-back portion and a concentric rearwardly projecting bell-standard portion, the latter being formed with a flat outer bearing-face having a central opening the edge 80 of which is set inward, in combination with a washer-like reinforce positioned within the outer end of the said standard against the said bearing-face and conforming to the internal diameter thereof and having an 85 inwardly set edge which is folded outward and over the inwardly set edge of the said opening therein so as not to project beyond the outer face thereof, the flat face of the standard and the reinforce being provided 90 with screw holes passing through the said face and through the reinforce on opposite sides of the said opening.

In testimony whereof, I have signed this specification in the presence of two subscribing witnesses.

FREDERICK C. HOFFMAN.
